CONVERSION AND SEPARATION OF THE
CONSTITUENTS OF ORGANIC MIXTURES
CONTAINING BOTH FATTY AND RESIN
ACIDS, PARTICULARLY TALL OIL

Frederick H. Gayer and Charles E. Fawkes, Chicago, Ill., assignors to Continental Research Corporation, Chicago Heights, Ill., a corporation of Illinois

No Drawing. Application July 17, 1939,
Serial No. 284,917

15 Claims. (Cl. 260—97.5)

This invention relates to a process for the separation of the major constituents of organic mixtures or oils containing both fatty and resin acids and especially to the clean, sharp and economic separation of the fatty and resin acids from such mixtures or oils, and particularly from tall oil. A more particular feature of our invention is the recovery of fatty and resin acids in the form of their commercially useful and valuable derivatives.

Tall oil is a by-product of sulphate pulp or kraft paper manufacture and is composed preponderantly of fatty acids, resin acids, unsaponifiable matter and coloring impurities. The unsaponifiable matter is composed of hydrocarbons and cyclic alcohols belonging to the group of phytosterols of which tall oil is an unusually rich source.

In our co-pending applications Serial No. 169,655 and No. 169,656 the latter now issued as Patent No. 2,223,850, both filed October 18, 1937, we have disclosed processes for the refining of crude tall oil and obtaining valuable by-products thereof. According to those applications we remove the coloring substances from crude tall oil and recover the commercially valuable phytosterol in a substantially quantitative yield and obtain a refined oil of light color and containing only a fraction of the unsaponifiable matter originally present. Crude tall oil also can be refined by distillation at reduced pressure. A greater portion of the fatty and resin acids and of the unsaponifiable matter distill over, the coloring matter and phytosterol remaining in the still residue. The tall oils refined by distillation are also of a considerably lighter color than the crude oil and also are essentially mixtures of fatty and resin acids with a rather high proportion of unsaponifiable matter.

Relatively little use has been made so far of either crude or refined tall oil, as the simultaneous presence of both fatty and resin acids is of great disadvantage. These components in themselves, however, as fatty and resin acids respectively are of great commercial importance. A large number of useful compounds are derived from these acids and find innumerable industrial applications. A process which effects a sharp separation of the components of tall oil is, therefore, of great commercial value, especially in view of the vast potential supply of tall oil, resulting from the increasing importance of the sulphate process for paper making. According to the process of the present invention hereinafter set forth we not only effect a clean and sharp separa-

tion of the fatty and resin acid portion of tall oil but obtain as a result of that separation derivatives of fatty and resin acids respectively, commercially more valuable than either fatty or resin acids in themselves.

Numerous processes have been proposed relating to the separation of the components of tall oil, and one such process is disclosed in our co-pending application Serial No. 169,654, which deals with the separation of the fatty and resin acids by a process involving esterification of the fatty acids, neutralization of the resin acids with an alkali metal base and separating the fatty acid esters from the resin acid soaps by means comprising furfural and water, and whereby we obtain as final products fatty acid esters and after acidifying the resin acid soaps, the free resin acids.

In distinction from our aforementioned process the present invention comprises esterification of the fatty acids, converting the resin acids into their zinc salts and separating the fatty acid esters from the zinc resinate. By this process we obtain high grade fatty acid esters and zinc resinate, both products of considerably greater commercial value than either tall oil or fatty and resin acids in themselves.

In the present process, as in Serial No. 169,654, we have taken advantage of the fact that the fatty acids in tall oil may be readily esterified with monohydric, aliphatic alcohols, such as methyl-, ethyl- or higher alcohols, whereas, given the proper conditions, the resin acids remain unchanged. This known chemical principle has been made the basis of a new and useful process of separation and is an integral part thereof, as hereinafter set forth. That is, the essence of this invention resides in taking together the old process of selective esterification of the fatty acid components carried out under controlled and specified conditions in combination with the new step of converting the resin acids into their zinc salts and separating the fatty acid esters from the zinc resinate by one of several possible methods.

The first step of our process contemplates the esterification of the fatty acids contained in tall oil, which may be effected by several methods, such as refluxing or otherwise reacting the tall oil with a monohydric alcohol, such as methyl- or ethyl alcohol, or a higher monohydric alcohol. The alcohol is preferably used in excess over that required for the quantitative esterification of the fatty acids. Esterification can be effected at or below the boiling point of the alcohol used in the presence of catalysts, such as, for example, sul-

phuric acid, or by any other conventional or suitable method. We prefer the esterification method disclosed in our copending application Serial No. 284,975, filed July 17, 1939, whereby esterification is effected in the absence of a catalyst at higher than atmospheric pressure. Esterification according to this method produces a mixture of fatty acid esters, resin acids, unsaponifiable matter, excess alcohol and the water formed in the esterification reaction. We have found that if we add to such a mixture zinc oxide in a quantity equivalent to the resin acids present, the resin acids are quantitatively converted into their zinc salts. On distilling off the excess alcohol and the water formed first in the esterification reaction and second in the reaction of the resin acids with zinc oxide, we obtain a mixture of fatty acid esters and zinc resinate as a mobile liquid of substantially the same color as the original tall oil.

The transformation of the resin acids contained in the esterified mixture into their zinc salts can also be effected in other ways. For example, in one modification we first distill off the excess alcohol and the water from the mixture obtained after esterification of the fatty acids and react the esterified oil so obtained with zinc oxide at a relatively low temperature, for example 100° C.

Another modification of our process consists in neutralizing the resin acids contained in the esterified oil with an alkali metal base, for instance, sodium hydroxide and converting the alkali resinate into zinc resinate by reacting them with the required amount of a solution of a zinc salt, such as zinc chloride or zinc sulphate. The zinc resinate formed dissolve into the fatty acid esters and we obtain the same liquid mixture as by reacting the esterified mixture directly with zinc oxide.

Of all these procedures we prefer the first one; namely, reacting the esterified mixture with zinc oxide before removing the excess alcohol. This procedure has a number of advantages, such as, (1) the presence of alcohol vapors above the surface of the mixture precludes the possibility of discoloration by contact with air, (2) convection currents in the low boiling mixture keep the powdered zinc oxide in suspension, eliminating the necessity of stirring (3) the excess alcohol takes up the water formed in the reaction of the resin acids with zinc oxide and also counteracts the tendency for a possible hydrolysis of the fatty acid esters which is promoted by zinc oxide, (4) due to the low boiling point of the mixture, which is only slightly higher than the boiling point of the alcohol used, pyrolytic changes do not occur.

The final step in our process consists in the separation of the fatty acid esters from the zinc resinate. We have found that this separation can be achieved by two entirely different methods. We have discovered that if a mixture of fatty acid esters and zinc resinate is distilled at a reduced pressure, such as for example a pressure of 20-50 mm. Hg. and at a temperature of about 180-240° C. the fatty acid esters will distill, whereas, under the same conditions, the zinc resinate are non-volatile and will remain in the still as residue.

Due to the peculiar character of the resin acids, 70 the distillation of the ester-zinc resinate mixture is often complicated by a solidification or "livering" of the zinc resinate in the first stages of heating. We have found that if the heating is continued the solidified white and quasi-crystal-

line zinc resinate become liquid again and dissolve in the esters which then can be distilled off, leaving a residue of clear, amorphous zinc resinate of resinous fracture and high melting point.

An alternative method for the separation of fatty acid esters from zinc resinate is based on extraction with solvents which dissolve the fatty acid esters but are substantially non-solvents for the zinc resinate, such as low molecular weight, aliphatic alcohols, for example, methyl-, ethyl- or isopropyl alcohol. For instance, methyl alcohol, which at ordinary temperatures is a poor solvent for the fatty acid esters of tall oil, becomes miscible in all proportions with these esters if the temperature is raised above the critical solution temperature, which in this case is 33° C. It has, however, substantially no solvent power for the zinc resinate and only such a quantity of zinc resinate will be dissolved as will be carried along with the esters. Decreasing the concentration of the esters in the solvent by using large quantities of the latter, for example about five volumes of solvent to one volume of the ester-zinc resinate mixture, will also decrease the total quantity of zinc resinate carried over into the ester solution. By this method we obtain zinc resinate substantially free of esters, the esters, however, are, as a rule, contaminated by small quantities of zinc resinate. After removing the solvent by distillation, we subject, therefore, the ester extract to a distillation at reduced pressure and obtain a high grade of pure fatty acid esters and a small quantity of zinc resinate as still residue.

As starting material for our process we prefer to use refined tall oil of a good color and of a low content of unsaponifiable matter, as the purity and color of the products will depend entirely on that of the starting materials used. The zinc oxide we use for the reaction with the resin acids is also of a pure grade and preferably of a fine particle size, such as two microns or less.

The following examples will illustrate our process, although we do not limit ourselves to the conditions as disclosed in these particular examples:

Example I

Four and one-half kilograms of refined tall oil are esterified with methyl alcohol until the acid number becomes constant at a figure of 65, corresponding to thirty-five percent resin acids calculated as abietic acid. To the cooled mixture one hundred and sixty grams of zinc oxide, having a particle size of less than two microns, are added and the mixture refluxed until the zinc oxide is dissolved. Distillation of the excess methyl alcohol and the water formed leaves 4.84 kilograms of a liquid residue of substantially the same color as the refined tall oil.

Example II

Three hundred grams of the ester-zinc resinate mixture obtained in Example I are distilled under reduced pressure with carbon dioxide as vapor carrier. We obtain one hundred fifty-four grams of pale yellow ester as distillate and one hundred sixteen grams of zinc resinate of high melting point as residue.

Example III

Five hundred grams of the ester-zinc resinate mixture obtained in Example I are heated under reflux with 2500 cc. methyl alcohol and the mixture left to settle at about 40° C. The clear

methyl alcohol-ester solution is decanted, the methyl alcohol distilled and the residue subjected to distillation under reduced pressure. We obtain as distillate two hundred seventy grams of pale yellow esters of a saponification value of one hundred eighty, and twenty-five grams of light colored zinc resinate as residue. The residue left after the extraction with methyl alcohol is heated at about 100° C. under reduced pressure to drive off occluded methyl alcohol. We obtain one hundred sixty-five grams of reddish yellow zinc resinate.

We claim as our invention:

1. The process of separating fatty acids from resin acids contained in tall oil, which comprises converting the fatty acids into their alkyl esters, converting the resin acids into their zinc salts and separating the alkyl esters of the fatty acids from the zinc resinate.

2. The process of separating fatty acids from resin acids contained in tall oil, which comprises converting the fatty acids into their alkyl esters, converting the resin acids into their zinc salts and separating the alkyl esters of the fatty acids from the zinc resinate by distillation.

3. The process of separating fatty acids from resin acids contained in tall oil, which comprises converting the fatty acids into their alkyl esters, converting the resin acids into their zinc salts and separating the alkyl esters of the fatty acids from the zinc resinate by extraction with a volatile solvent which is substantially a non-solvent for zinc resinate.

4. The process of separating fatty acids from resin acids contained in tall oil, which comprises converting the fatty acids into their alkyl esters, reacting the resultant mixture with zinc oxide to convert the resin acids into their zinc salts and separating the alkyl esters of the fatty acids from the zinc salts.

5. The process of separating fatty acids from resin acids contained in tall oil, which comprises converting the fatty acids into their alkyl esters, reacting the resultant mixture in an alcoholic solvent with zinc oxide to convert the resin acids into their zinc salts, removing the solvent and separating the fatty acid esters from the zinc resinate.

6. The process of separating fatty acids from resin acids contained in tall oil, comprising reacting the tall oil with a monohydric aliphatic alcohol to esterify the fatty acids, converting the resin acids into their zinc salts and separating the fatty acid esters from the zinc resinate.

7. The process of separating fatty acids from resin acids contained in tall oil, comprising reacting the tall oil with an excess of a monohydric aliphatic alcohol to esterify the fatty acids, reacting the resultant mixture with zinc oxide to convert the resin acids into their zinc salts, removing the excess alcohol and the water formed, and separating the fatty acid esters from the zinc resinate.

8. The process of separating fatty acids from resin acids contained in tall oil, which comprises

converting the fatty acids into their alkyl esters, neutralizing the resin acids with aqueous alkali, reacting the mixture with a solution of a zinc salt to convert the alkali resinate into zinc resinate, removing the formed water and separating the fatty acid esters from the zinc resinate.

5 9. The process of separating tall oil into fatty acids and resin acids, which comprises converting the fatty acids into their alkyl esters, converting the resin acids into their zinc resinate and heating the mixture until a portion of the zinc resinate precipitates, continuing heating until the precipitated zinc resinate dissolve again, and distilling the fatty acid esters from the zinc resinate.

10 10. The process of separating tall oil into fatty acids and resin acids, which comprises converting the fatty acids into their alkyl esters, converting the resin acids into their zinc resinate and distilling the fatty acid esters from the zinc resinate while maintaining the mixture under a subatmospheric pressure.

15 11. The process of separating tall oil into fatty acids and resin acids, which comprises converting the fatty acids into their alkyl esters, converting the resin acids into their zinc resinate and extracting the fatty acid esters with a volatile solvent which is substantially a non-solvent for zinc resinate, removing the solvent and recovering the fatty acid esters.

20 12. The process of separating tall oil into fatty acids and resin acids, which comprises converting the fatty acids into their alkyl esters, converting the resin acids into their zinc resinate and extracting the fatty acid esters with a volatile solvent which is substantially a non-solvent for zinc resinate, removing the solvent and purifying the fatty acid esters by distillation.

25 13. The process of separating tall oil into fatty acids and resin acids, which comprises converting the fatty acids into their alkyl esters, converting the resin acids into their zinc resinate and extracting the fatty acid esters with a low molecular weight aliphatic alcohol at a temperature above their critical solution temperature, separating the fatty acid ester extract solution from the zinc resinate, removing the solvent from the solution by distillation and recovering the fatty acid esters.

30 14. In the process of separating tall oil into fatty acids and resin acids the step which comprises converting the tall oil into a mixture of alkyl esters of fatty acids with zinc resinate by esterifying first the fatty acids with a monohydric aliphatic alcohol and subsequently converting the resin acids into zinc resinate.

35 15. In the process of separating tall oil into fatty acids and resin acids the step which comprises converting the tall oil into a solution of zinc resinate in alkyl esters of fatty acids by esterifying first the fatty acids with a monohydric aliphatic alcohol and subsequently converting the resin acids into zinc resinate.
